UNITED STATES PATENT OFFICE.

ORLANDO C. KETRING AND JACOB LE ROY KETRING, OF PORTLAND, INDIANA.

CENTRIFUGAL PROPELLER.

Application filed May 14, 1923. Serial No. 638,772.

To all whom it may concern:

Be it known that we, ORLANDO C. KETRING and JACOB LE ROY KETRING, both citizens of the United States, residing in the city of Portland, in the county of Jay, State of Indiana, have invented a new and useful Centrifugal Propeller, of which the following is a full, clear, and comprehensive specification and exposition, the same being such as will enable others to construct and use the same.

The object of our present invention, broadly speaking, is to provide a centrifugal propeller which will be simple in character, strong and durable in construction, easily operated and controlled, comparatively light in weight, efficient in practice, and which can be manufactured and sold at a comparatively low price.

More specifically stated, our object is to provide a propeller for boats or water-craft, whereby a constant and unvarying propelling power may be applied and controlled and, if desired, constantly maintained, and by which the boat or the like may be operated either forwardly or rearwardly without the reversal of the engine or motor and whereby the reversal of the propeller may be instantly accomplished by a single movement by the operator.

Other objects and particular advantages of the invention will be brought out in the course of the following description, and that which is new will be correlated in the appended claims.

The invention comprises a power plant, as a motor or engine; a centrifugal driver or generator; and the propeller proper by which a column of water of great velocity is directed against the water in which the boat is floated.

The preferred means for carrying out the principles of our invention in a practical manner is shown in the accompanying drawings, in which—Figure 1 is a side elevation of our invention as assembled in connection with a gasoline engine or motor.

Figure 2 is a top plan view of the same. Figure 3 is a contact face view of the centrifugal pump or generator, the rearward parts being removed therefrom. Figure 4 is a central vertical section of the propeller mechanism. Figure 5 is an inside face view of the propeller parts in elevation. Figure 6 is a cross section of the propeller, as

taken on the line 6—6 of Fig. 5. Figure 7 is an outside view of the controller or valve. Figure 8 is a cross section, as taken on the line 8—8 of Fig. 7. Figure 9 is another outside view of the controller valve, as taken at right-angles to Fig. 7. Figure 10 is a perspective view of the valve core. Figure 11 is a cross section of the valve core and its cylinder, indicating the upward movement of water therethrough. And Figure 12 is a cross section of the valve core and the cylinder, indicating the downward movement of water therethrough.

Similar indices denote like parts throughout the several views.

In order that the construction, the operation, and the several advantages of our invention may be more fully understood and appreciated we will now take up a detailed description thereof, in which we will set forth the same as fully and as comprehensively as we may.

With the main portion 1 of the motor we are not particularly concerned in this invention, as it is of ordinary construction and operation, and the type of motor may be changed as desired.

However said motor has a driving or power shaft 2, by which the centrifugal pump or generator is rotated, as hereinafter explained.

Our invention is to be carried by the rear portion or end of a boat, represented by numeral 3. A pair of screw clamps 4 (one on each side) are formed integral with the lower portion of the motor 1, and by which the motor is removably secured to the part 3 of a boat, as shown in Fig. 1. Said clamps are disposed at an angle, corresponding to the angle of the part 3, whereby the motor is held relatively horizontal in operative position, as shown in Fig. 1.

Rigidly secured to the rear end of the motor, and concentric of the shaft 2, is the pump or generator case 5, in which is the centrifugal rotator 6, a portion of which is shown in Fig. 3, but we make no claim thereto, as this is also of ordinary construction.

In the center of the rear of the case 5 is a rearwardly directed round contact face 7, concentric with which is an intake opening, shown in Fig. 3, through which water may be drawn to the center of the rotator and therefore into the center of the case 5.

Extending down from the periphery of

the lower portion of the case 5 is a projection 8, having a rearwardly directed face 9, through which is the angular discharge aperture 10, which connects with the interior of the case 5 near the periphery of the rotator 6.

10 The fittings 11 are carried by the periphery of the case 5 and connect with the interior thereof, and they are connected with the pipes 12, the other ends of said pipes being connected into the water jacket of the motor, and through which water is circulated around the movable parts of the motor.

15 Formed by a single casting are the intake hood 13, the two-way box 14, and the valve or controller casing or cylinder 15, all arranged substantially vertical with relation to each other.

20 The inlet hood 13 has a face 16, which is adapted to fit in contact with the face 7, where they are secured together, as by screws or bolts 17. The interior 18 of the hood 13 opens into the central portion of the 25 casing 5, through the aperture inside the face 7, and at its lower end the interior 18 opens into the space 19 which latter passes through the box 14 and opens into the cylinder 15.

30 An outlet space 20 is also formed in the box 14, which registers with the aperture 10. Said box 14 has a projecting flange forming a face 21 which is adapted to be secured to the face 9 by means of screws or 35 bolts inserted through apertures in the faces 9 and 21.

The lower end of the space 20 opens into the interior of the cylinder 15, to one side of the space 19, as in Fig. 4.

40 Integral with and extending down from the underside of the cylinder 15 is a projection 22, which has a partition 23 extending vertically therethrough, thereby forming passage-ways 24 and 25 extending from the 45 interior of cylinder 15. The passage-way 24 being directly opposite the space 19, and the passage-way 25 being directly opposite the space 20, substantially as shown.

50 A flange 26 extends out from the lower end of the projection 22.

Finally, secured to the lower end of the projection 22, is the discharge head, comprising an upper portion 27 whose upper end carries a flange 28 which contacts with the flange 26 and to which is it secured by bolts 29. The lower portion of said head forms a horizontal bottom 30. The said head tapers down latterly, and tapers upward forwardly and rearwardly, substantially as shown in Figs. 4 and 5. A vertical partition 31 connects with the partition 23 and it extends down to the bottom 30, thereby forming two compartments 32 and 33, as shown. A forwardly directed nozzle portion 34 opens from the compartment 32;

and a rearwardly directed nozzle 35 opens from the compartment 33.

The core which fits revolvably in the cylinder 15 is shown most clearly in Figs. 7, 8, 9, 10, 11 and 12, and it comprises the closed heads 36 and 37 and a central partition 38. A shaft 39, concentric of the core, is secured to the partition 38 and the end 36, and it projects out some distance from the latter, whereby the core may be turned. 75

The front end of the cylinder 15 has a solid or closed head 40, in the center of which is an aperture through which may project the shaft 39, and around which is a packing-box or gland 41. The rear end of the cylinder is adapted to be closed by the cap plate 42, which is removably bolted thereto as shown. 80

Secured on the projecting portion of the shaft 39 is an arm 43, and pivoted to said arm is the link 44. Numeral 45 denotes the control lever, which is mounted near its center on the pivot bolt 46. And the upper end of the link 44 is pivoted to the rear end of the lever 45, whereby the raising and lowering of the forward end of the lever 35 will rotate the said core, for the purposes hereinafter explained. 90

In practice it is evident that the revolving of the rotator 6 at a high rate of speed 95 will, after being primed, cause suction of water through the space 18 into the interior of the case 5, and cause it to discharge out through the aperture 10, therefore to control the flow of water in order to accomplish the 100 results desired is the purpose of the rotatable core, and this is attained as follows: The peripheral surface of the core is adapted to slide in contact with the interior wall of the cylinder 15, there being a plurality 105 of openings through the surface of the core, the same being arranged in pairs laterally with relation to each other, said openings being adapted to register with the opening in the lower apertures 19 and 20, and 24 and 25, and certain portions of the face of the core are adapted to close said apertures 19—20 and 24—25. Therefore it is evident 110 that when the faces A and B are directly upward, or downward, they will close the lower ends of the spaces 19 and 20, respectively, or the upper ends of the spaces 24 and 25, respectively, thereby preventing the flow of water to or from the pump, therefore there would be no propelling agent at 115 work. Then if the core be turned whereby it will stand as in Figs. 11 and 12, it is evident that the water may pass upward from the compartment 32, through the passage denoted by the arrows *a* in Fig. 11; and at the same time it may flow downward from the space 20 into the compartment 33, passing through the passage-way denoted by the arrows *b* in Fig. 12, thereby permitting the 120 pump to draw water in through the nozzle 125

130

34 and discharge it through the nozzle 35, thereby driving the boat forward.

Now if the core be turned to position whereby the faces C and D, Fig. 7, will be 5 directly upward then the face C will be about half-way over the lower end of the space 19 and the face D will be about half-way over the lower end of the space 20, then the intake and the discharge of water, with 10 relation to the nozzles, will be reversed that is to say: The water will enter through the nozzle 35 (as this will finally lead to the intake of the pump) passing upward it will enter the opening F, engage the closed side 15 of D, then will pass to the right through the notch 50 in the partition 38, to the baffle 49 from which it will pass upward past the open side of the face C into the space 19, and from there to the intake of the pump. 20 At the same time the water from the pump will enter the space 20, pass down past the open side of the face D into the space F where it will encounter the baffle 47 and be directed through the notch C into the space 25 E, and from there will pass into the passage 24 to the compartment 32, and then out through the nozzle 34, thereby causing the two streams of water to cross each other in the core, by which the intake and the discharge 30 of the nozzles will be reversed but without reversing the motor, and thereby causing the boat to travel rearward, but of course at a reduced rate of speed, as the volume of water passing through the core 35 is partly cut down by reason of the faces C and D.

The steering device comprises a bracket 48 secured to and extending back from the lower portion of the head 13, and it carries 40 a bearing 49 in which is rotatably mounted the shaft 50, the lower end of said shaft being pivoted in the bearing 51 which extends upward from the nozzle 35. A blade 52 extends back from the shaft 50 to which it is secured. Steering-arms 53 and 54 are secured to the upper end of the shaft 50, and they extend opposite to each other and at right angles to the blade 52.

In practice the boat 3 floats in a body of 50 water, with the water level at approximately the flanges 28 and 29. The entire device is secured to the rear end of the boat by the clamps 4 which function by means of the clamp screws 55.

If now the motor be started, as by turning the crank 56, it is evident that the pump, after being primed through the primer 57, will revolve the rotator 6 at a high rate of speed, causing the water to be drawn, from 55 the body of water in which the boat floats, through one of the nozzles and discharged through the other nozzle, the discharge of water through the nozzle 35 will cause the boat to be pushed forward at the speed desired, the speed depending on the degree to

which the core in the cylinder is turned to open the ports for forward movement.

When the direction is reversed, that is when the boat is being driven rearward, the maximum speed will be about one-half that 70 of the forward movement, as the ports can then only be half opened, as herein set forth.

By attaching ropes to the outer ends of the arms 53 and 54 and extending them forward to the boat, it is evident that the boat 75 can be steered to the left by pulling on the arm 53, and can be turned to the right by pulling on the arm 54. When both arms are released, and the boat is being propelled forward, the boat will move directly forward without manipulating the steering device, as the discharge through the nozzle 35 striking the lower portion of the blade 80 will cause the blade to extend directly rearward unless this inclination is overcome by a 85 person pulling on one of said arms.

The predominant feature of our invention resides in the propulsion of boats by the discharge of water under great velocity into the body of water in which the boat 90 floats whereby the boat is propelled in a direction opposite to that of the water being discharged.

We desire that it be understood that various changes may be made in the several 95 details of construction without departing from the spirit of the invention and without sacrificing any of the advantages thereof which are new and useful.

Having now fully shown and described 100 our invention, what we claim, and desire to secure by Letters Patent of the United States is—

1. Means for propelling boats comprising a centrifugal pump, a motor for rotating 105 the pump, means for securing the device to the rear end of a boat, a forwardly directed nozzle and a rearwardly directed nozzle both located below the surface of the water in which the boat floats, means for conducting water through one of said nozzles to the intake of the pump by the suction of the pump, means for conducting the water from the pump out through the other nozzle under pressure of the pump, and means for 110 changing the intake and outlet of water from one to the other of said nozzles without changing the flow of the water through the pump.

2. A propeller for boats comprising a centrifugal pump, a motor for rotating the pump in one direction only, an intake hood connected with the interior of the central portion of the pump, a two-way box integral with said hood, a cylinder connected 115 with said box, a projection extending down from said cylinder and directly opposite to said two-way box, a vertical partition dividing the interior of said projection, a head extending down from said projection 120

125

130

and having a bottom at its lower end, a vertical partition dividing said head and extending from the first named partition to said bottom and dividing the head into a forward and a rearward compartment each having an opening which openings are directed forward and rearward, respectively, and a core rotatable in said cylinder to control the flow of water to and from said 10 openings in the head.

3. A propeller for boats comprising a pump, means for operating the pump, a cylinder spaced from the pump, means for conducting water between the cylinder and 15 both the intake and the discharge of the pump, a head located below the cylinder and adapted to convey water both upward and downward at the same time, a core rotatably mounted in said cylinder and 20 adapted to be turned to change the direction of flow of the water through said head, all substantially as shown.

4. A propeller for boats comprising a pump for drawing water thereto and forcing it therefrom, a cylinder located below 25 said pump, a double nozzle head located below the cylinder, there being a channel entering the head from the rear and extending upward to the intake or the discharge of said pump, there also being a second channel entering the head from the 30 front and extending upward to the intake or the discharge of said pump, a core rotatable in said cylinder and adapted, when 35 turned in one position, to permit the two streams of water to extend therethrough parallel with each other or when turned to another position to cause said streams of water to cross each other and by which

when turned to still another position will 40 shut off both streams of water.

5. In combination with a pump and means for operating the pump, a head forming two nozzles which are directed in opposite directions to each other, means for 45 conducting water from one of said nozzles to the intake of the pump, means for conducting water from the other one of said nozzles to the discharge of the pump, a valve located intermediate said nozzles and 50 the pump, the core of said valve being adapted to be turned to permit two streams of water to flow therethrough in directions opposite to each other or when turned to another position will cause said streams of 55 water to cross each other therein, whereby the two streams of water may be reversed as to the intake or the discharge of the nozzles without changing the direction of the flow of water into or from the pump, all 60 substantially as shown and described.

6. A construction of the nature set forth including a cylinder having an inlet and an outlet at the top and an inlet and an outlet at the bottom, a core rotatably mounted in said cylinder, said core being formed to permit two streams of water to flow through the cylinder at one time in directions opposite to and parallel with each other, said core also having means to cause 70 two streams of water to cross each other therein, and also said core having means for shutting off the flow of both streams of water therethrough, and means whereby said core may be rotated.

ORLANDO C. KETRING.
JACOB LE ROY KETRING.
